UNITED STATES PATENT OFFICE.

OSCAR WINTER, OF PHILADELPHIA, PENNSYLVANIA.

SECTIONAL TABLE-PAD.

No. 902,037.

Specification of Letters Patent. Patented Oct. 27, 1908.

Application filed September 26, 1907. Serial No. 394,621.

To all whom it may concern:

Be it known that I, OSCAR WINTER, a citizen of the United States, residing at Philadelphia, in the county of Philadelphia and State of Pennsylvania, have invented new and useful Improvements in Sectional Table-Pads, of which the following is a specification.

This invention is for the protection of polished dining table tops, to prevent their disfigurement from hot dishes. When the tables are covered with a blanket under the table cloth, as generally heretofore in use, they are not sufficiently protected to prevent the blistering of the polished surface, or the adhering of the blanket thereto, which causes white blemishes. To overcome the objections enumerated segregated pads of non-flexible and non-heat conducting material, are removably secured within an outer covering of soft material, subdivided into suitable pockets by removable tapes or cords, which permit the folding together of a series of pads, within the several pockets of the cover, into a small space when not required for use, and especially a covering which permits the removal of the several pad sections and the tapes or cords from the cover when it needs to be laundered.

The invention is illustrated in the accompanying drawing wherein like parts are indicated by like reference characters, in which

Figure 1 represents the covering of a round table with an interposed extension leaf. Fig. 2 is a section, on an enlarged scale, on line *xx*-Fig. 1. Fig. 3 is also a section, on an enlarged scale, on line *yy* Fig. 1.

The illustration, Fig. 1, is of a circular table with one extension, but it will be obvious that any table with a different top may equally well be covered, by shaping and arranging the parts to suit its contour. For the table top shown, each end section 1, 2 of the covering will consist of two pieces of material 3, 4 cut to shape, laid together with their wrong sides outward and their outer circular edges 5 will then be permanently stitched together, they will then be turned right side out to form a receptacle wherein to insert the pad sections without any attachment to the covering. The pad sections are preferably composed of compressed wood

pulp 6, coated with a silicate-soda solution 7, which permanently unites a covering 8 of asbestos paper to the wood pulp 6, and these component parts form an inflexible body impervious to moisture, and a non-conductor of heat to the extent desired for the purpose employed. For the purpose of folding and storing in a small space the cover sections 1, 2 are subdivided into convenient compartments 8', 9, 10 by interlacing the cover parts 3, 4, preferably with chalk line or tapes 11 which can be withdrawn when the cover needs to be cleansed. The inner edges 12 of the covers 3, 4 are folded in as seen at 13 in Fig. 3 for strength and drawn together sufficiently to secure the pad sections in place by sewing 14 of a temporary character, easily removable when the pad sections are to be removed from the cover. The intermediate section covers 15 are permanently sewed together on edges 16, 17, 18 and left open on edge 19 for the insertion of their pad sections 20, 21, the edge 19 is then closed by temporary sewing, and tapes 22 are interlaced through covers 15 to segregate sections 20, 21 and permit folding.

I claim.

1. In a table top protection, a covering formed of an upper and lower part permanently secured together for a portion of their edges to thereby form a receptacle which is open at the free portion of the edges for the insertion of sectional pads; removable means to subdivide the cover and segregate the pad sections, and means at the cover's free edges to removably secure the pad sections.

2. A plurality of pad sections, an outer covering therefor fashioned to have an opening whereby the pad sections may be inserted within the covering; removable means to close the opening; and means to segregate the pad sections, comprising a strip of material interlaced through the outer coverings, between the pad sections, and removable when the outer covering needs to be cleansed.

In testimony whereof I affix my signature in presence of two witnesses.

OSCAR WINTER.
